Jacob Howton, Andrew C. Brinman, and Jonas Ingraham,
Gallows Patent

The solecile referred to in these Gallows Patent and making part of the same containing a description in the words of the inventors Jacob Howton, Andrew C. Brinman, and Jonas Ingraham themselves of their improvement in the Dry Dock.

To all to whom these presents shall come, Jacob Howton, Andrew C. Brinman and Jonas Ingraham of the City of Buffalo, County of Erie and State of New York send greeting. Be it known that we the said Jacob Howton, Andrew C. Brinman and Jonas Ingraham have invented a new and useful improvement, not known or used before in the making of a marshy constructed Dry Dock by which a very important advantage is gained over the dry docks or rail ways now in use for repairing vessels, boats or other naval craft. This improvement consists in having a large reservoir placed a convenient distance from the sides of the dock the floor or bottom, of which reservoir, to be on a level with the tops or coping of the sides of the dock, and which reservoir is to be filled, by means of a pump from the water below or on the floor of the dock. From the side of said reservoir is a conductor or floodstock, leading the water from the reservoir into the dock, to raise the vessel high enough to float the same on the cradle, after the vessel shall have been brought on the centre of the cradle. The cradle is composed of a central stationary block and slide blocks which are movable with a hand rod or rod in the outer ends of each slide block to operate in any depth. The flood gates are then to be hoisted which leaves the water from the cradle and leaves the vessel and cradle dry. While the vessel is repairing the reservoir is to be filled again after the vessel is repaired. The gates are to be closed and the dock is to be filled by taking the water from the reservoir by means of the floodstock as before.

for sufficient to float the vessel from the cradle into the water
than by hauling the floor gates, the vessel bows down, by
which time the back gates are open and the vessel set afloat.

The claim the invention of a new, simple & safe system of
the vessel according to be filled with water and to
be used in raising or lifting down of the boat or other craft
as an improvement upon the method of raising vessels.

before used also the improvement of the slide blocks by
means of a hand in each slide block (hopping into bag)
which set on a ground which will not move we have
invented and subscriber before the clerk of the day of Jan-

uary 24th 1836.
